UNITED STATES PATENT OFFICE.

DAVID L. SUMMEY, OF WATERBURY, CONNECTICUT.

CONVEYER FOR HEATING FURNACES.

Original application filed July 28, 1923, Serial No. 654,295. Divided and this application filed March 26, 1927. Serial No. 178,650.

This invention relates to conveyers and particularly to conveyers for heating furnaces. This application is a division from an application filed July 28, 1923, Serial No. 654,295.

5 It is an object of the invention to provide an endless conveyer having an effective link connection for use under conditions in which ordinary lubrication is impossible. It is a further object of the invention to provide a 10 conveyer such that the danger of broken parts dropping out is avoided.

With these general objects, and others, in view, the invention consists in the features, combinations, details of construction, and arrangements of parts which will first be described in connection with the accompanying drawing and then more particularly pointed out.

In the drawing—

20 Figure 1 is a diagrammatic view illustrating, in section, part of a heating furnace having a conveyer embodying the invention;

Figure 2 is a sectional view through a link connection;

25 Figure 3 is a view in end elevation of two adjacent links, with parts broken away and in section; and,

Figure 4 is a view in side elevation of a connecting shackle removed.

30 Referring to the drawing, 11 indicates a furnace chamber. Within this chamber is an endless conveyer chain, the individual links in the embodiment illustrated being buckets 12 for conveying small articles. These buckets, connected as later described, have flat bottoms which ride on supporting rails 13. At each end of the furnace the chain passes over a hexagon-shaped pulley 14, one of these pulleys being shown in Fig. 1. Either 35 of the pulleys may be rotated in any suitable manner to drive the chain. Above the top face of pulley 14 is a feeding chute 15, by means of which the articles to be heat treated 40 may be delivered to the passing buckets. The heated articles may be received at the far end of the furnace in any suitable manner, for example, by the quenching tank shown and described in the parent application referred to.

45 The furnace chamber may be heated in any suitable manner, for example, by electric resistance units indicated at 16. Such heating units are more fully described and shown in the parent application referred to.

50 To connect the chain links, e. g. the buckets 12, in the embodiment here illustrated as an

example, each bucket has on one side a pair of perforated lugs 20 and on the other side a pair of perforated yokes, i. e. double lugs, 21. When the buckets are assembled side by side in chain position, the yokes 21 of one bucket straddle the lugs 20 of the adjacent bucket (Fig. 2) with the respective perforations in alignment. A pivotal connection is made by a cylindrical pin 22 which passes through the aligned perforations of each set. These pins are made of a metal having wearing qualities and capable of withstanding continued high temperatures. For this purpose nickel-chromium alloy has been found suitable. In the present embodiment the buckets 12, as well as 60 the pins 22, are made of nickel-chromium alloy. 65

With the construction described the links, e. g. the buckets 12, are effectively connected into endless chain form in a simple manner. 70 The chain as a whole is capable of withstanding continued high temperatures, and continued operation without undue wear in its pivots, and no lubrication is necessary.

75 There is provided means for preventing the pivot pins or broken pieces thereof from dropping out. As here shown as an example, straddling each assembled yoke and lug, in the manner illustrated in Fig. 2, is a shackle 23. One end or arm of this shackle, the left end in Figs. 2 and 4, has a bore 24 therethrough which aligns with the perforations of lug 20 and yoke 21 and is of a like diameter. The other end of the shackle, the right end, in Figs. 2 and 4, has a recess 25 for receiving 80 the end of the pivot pin. Opening out of recess 25 is a bore 26 of smaller diameter which forms with the recess a shoulder 27. To assemble the parts, the pin 22, which is of a length to extend beyond the yoke at each 85 end, is inserted through bore 24 and pushed home into recess 25 until its far end engages shoulder 27. In this position the pin has its ends journaled in the shackle. 90

95 Endwise movement of the pin 22 in one direction is prevented by its engagement with shoulder 27. To prevent endwise movement in the other direction blocking means for bore 24 is provided. As here shown as an example, the shackle has a transverse boss 29 which is drilled with two holes (shown in Fig. 4) at right angles to the axis of the bore 24 and so located that each hole grooves the wall of the bore. After the pin 22 is assembled, a cylindrical plug 30 of pin diameter is in- 100

serted in the open end of the bore 24. This plug is grooved to form, in connection with the grooves in the wall of bore 24, passageways for two locking pins 31. These locking pins are inserted through the holes formed in boss 29 and lock plug 30 in place.

With the construction described, the pivot pin 22 cannot drop out as its endwise movement in either direction is prevented, nor can pieces of the pin drop out in case the pin should break. Thus, there is avoided any danger of short circuiting by loose pieces of metal in a furnace electrically heated. The parts are readily assembled and disassembled. In disassembly, the removal of locking pins 31 permits removal of plug 30. The plug being released pivot pin 22 and plug can be knocked out by a suitable tool applied through bore 26. With the buckets and connecting elements made of nickel-chromium or an equivalent, the conveyer is capable of withstanding continued high temperatures.

What is claimed is:

1. In combination, a plurality of conveyer links, overlapping perforated lugs on adjacent links, pivot pins passing through said perforations to connect the links into the form of an endless conveyer chain, shackles straddling the overlapping lugs and in which the ends of the pins are journaled, the shackles having means for preventing endwise movement of the pivot pins.
2. In combination, a plurality of conveyer links, overlapping perforated lugs on adjacent links located in close proximity one to the other, pivot pins passing through said perforations to connect the links into the form of an endless conveyer chain, shackles straddling the overlapping lugs and in which the ends of the pins are journaled, said shackles being of a length to have the ends thereof

in close proximity to the overlapping lugs, the shackles having means for preventing endwise movement of the pivot pins.

3. In combination, a plurality of conveyer buckets, overlapping perforated lugs on adjacent buckets, pivot pins passing through said lugs to connect the buckets in the form of an endless chain, shackles straddling said overlapping lugs and having openings for receiving the ends of said pins, one of said openings in a shackle being of a size to pass the pin, and means for blocking said opening after assembly of a shackle and pin.

4. In combination, a plurality of conveyer buckets, overlapping perforated lugs on adjacent buckets, pivot pins passing through said lugs to connect the buckets in the form of an endless chain, shackles straddling said overlapping lugs and having openings for receiving the ends of said pins, one of said openings in a shackle being of a size to pass the pin, a plug for blocking said opening after assembly of the shackle and pin, and means for locking the plug in place.

5. In combination, a plurality of conveyer buckets, overlapping perforated lugs on adjacent buckets, pivot pins passing through said lugs to connect the buckets in the form of an endless chain, shackles straddling said overlapping lugs and having openings for receiving the ends of said pins, one of said openings in a shackle being of a size to pass the pin, the other opening being reduced in size beyond the pin to prevent passage of the pin but to give access thereto, and means for blocking the first named opening after assembly of shackle and pin.

In testimony whereof, I have hereunto set my hand.

DAVID L. SUMMEY.
